H. L. FISCHER

SHOW CARD STENCILING DEVICE

Filed Feb. 15, 1926

Patented May 4, 1926.

1,582,920

UNITED STATES PATENT OFFICE.

HOWARD L. FISCHER, OF ST. PAUL, MINNESOTA, ASSIGNOR TO AGNES HICKEY, OF ST. PAUL, MINNESOTA.

SHOW-CARD-STENCILING DEVICE.

Application filed February 15, 1926. Serial No. 88,408.

To all whom it may concern:

Be it known that I, HOWARD L. FISCHER, a citizen of the United States, residing at St. Paul, in the county of Ramsey and State 5 of Minnesota, have invented a new and useful Improvement in Show-Card-Stenciling Devices, of which the following is a specification.

This invention relates to improvements 10 to show card stenciling devices wherein it is designed to provide a stenciling apparatus having a condensed and compact nature, and wherein stencils may be carried together with material to be stenciled on and also 15 stenciling brushes and paint.

This application is designed to carry out the principles and functions set forth in my application Serial No. 659,966 for show card and stenciling devices and in this construction 20 I provide a simple stenciling device which can be made economically, yet having all of the features necessary to provide a complete and compact stenciling cabinet.

A feature of the invention resides in providing 25 a cabinet wherein the stencils, the clamping member for holding the material to be stenciled, together with the tray means for supporting the stenciling paint and brushes and other material may be contained 30 in a compact nature. This construction permits the manufacture of a simple, inexpensive stenciling cabinet, complete in itself, having means of folding in manner to conceal the stencils and stenciling material in 35 a neat and compact manner.

It is also a feature of the invention to provide a particular clamping means for holding the work to be stenciled, which is operated by lever means which engages 40 with the stenciling cabinet when the same is held in open position and which is operable to permit the releasing of the clamping member by moving the cabinet in a perpendicular or forwardly inclined position. 45 The clamping member is supported on the cover of the cabinet, being pivoted in a manner so that the lever projecting from the same is adapted to engage the cabinet in a manner so that the cabinet when moved 50 in a backward or inclined position will force the clamping against the work table to hold the material firmly thereon. When the cabinet is moved forwardly it automatically releases the clamping member from the work 55 table permitting the work beneath the

clamping member to be moved as may be desired.

The simplicity of my stenciling device is important, having a small number of cooperating parts which are adapted to be moved 60 automatically into operating position when the cabinet is opened and having automatic means for releasing the clamp and causing the same to fold concealed within the cabinet. 65

These features, together with other objects of the invention, will be more fully and particularly set forth and pointed out in the following specification and claims:

In the drawings forming part of this 70 specification Figure 1 is a perspective view of my cabinet in closed position, having the operating parts concealed therein.

Figure 2 is a perspective view of the cabinet in open position ready for operation. 75

Figure 3 is a cross section on the line 3—3 of Figure 2.

Figure 4 is a detail partly in section, illustrating the cover holding and hinging means. 80

In the drawings my stenciling cabinet A is designed to provide a compact device wherein the stencils may be completely enclosed to protect the same and to enclose 85 the clamping mechanism.

The cabinet A is formed with a rectangular compartment or casing 10, to which is pivotally secured the cover 11 by means of the hinges 12. These hinges are made in the form of a bracket being attached at 13 to 90 the cover and pivotally secured at 14 to the body 10 of the cabinet A.

The cover 11 of my cabinet A is adapted to form the work table on the inner surface 15 of the same, so that articles to be stenciled 95 may be laid out flat upon this table which, when in open position, as illustrated in Figures 2 and 3, extends out from the front of the cabinet A and forms a support to hold the body of the cabinet 10 in upright 100 position with the inner compartment 16 of the same exposed and open.

Within the compartment 16 I provide a stencil holding tray 17, in which the stencils 18 are adapted to be supported in the ordinary manner. This permits the stencils to be readily accessible when the cabinet is in open position, as illustrated in Figure 2. Projecting from the tray 17 I provide 105 a shelf 19 on which the paint jars may be 110

supported together with stenciling brushes and other articles used in connection with making stencil copies with my show card stenciling device.

5 The cover 11 is adapted to support the clamping mechanism B. The clamping mechanism B is made up of a longitudinally extending clamping bar 20, which is supported by one end of the arms 21 in a 10 manner so as to project across the work table 15 of the cover 11. By means of supporting brackets 22 the supporting arms 21 are pivotally held to the work table.

15 The free ends 23 of the arms 21 are adapted to extend into the compartment 16 of the cabinet A in a manner so that when the body 10 of the cabinet is in slightly 20 backwardly inclined position, as illustrated in Figure 3, the clamping bar 21 is held clamped against the work surface 15 of the cover 11. By these means in construction the body of the cabinet A is adapted to hold the clamping bar 20 sufficiently tight against the work table 15 so that material may be 25 readily clamped firmly beneath the same while it is being stenciled. The free ends 23 of the arms 21 are positioned in a manner to operate in conjunction with the stop members 24, which are positioned in the compartment 16, so as to project outwardly from the sides of the ends of the cabinet to engage these free ends 23 to cause the arms 21 to be lifted when the body, cabinet A, is moved forward or into a perpendicular 30 position, as illustrated in Figure 3, or during the act of closing the cabinet A. This permits the lifting of the clamping bar 20 as soon as the stops 24 press against the free ends 23 of the arms 21, releasing the work beneath the bar 20. The arms 21 are 35 of a material to provide sufficient spring or resiliency so that a slight spring pressure may be exerted against the clamping bar 20 when the cabinet body 10 is moved backwardly so that the edge 25 of the cabinet A bears against the under side of the arms 21 adjacent to the free ends thereof.

40 The hinge supporting brackets 12 are adapted to position the cover and work table in a manner so as to provide a space 45 between the surface 15 of the work table and the lower edge 27 of the cabinet A. This permits streamers and articles of practically any length to be passed through the clamping means B and beneath the cabinet A.

50 The simple inexpensive construction of my stenciling device provides a stenciling cabinet of a very desirable nature, having 55 a small number of parts which can be manufactured economically and of small dimensions if it is desired or of any suitable size to take large or small stencils, thereby providing a very desirable stenciling means 60 and apparatus.

The cover 11 is adapted to be held in a set position or in frictional engagement with the body 10 by the bracket hinges 12 which are pivotally attached at 14. The pivotal attachment 14 of the hinges 12 is 70 of a construction provided with an adjusting thumb nut 28 which can be tightened so as to increase or decrease the friction between the hinge 12 and the body of the stenciling cabinet. The function of this means of securing the same is to permit the body 10 to be held in a set position in operation of the device.

75 The important feature of this invention resides in the automatic operation of the clamping means by the tilting of the body or cabinet of my stenciling device. In other words, the cabinet when tilted operates the clamping bar either into clamping engagement with the work table or disengaging it from the same so as to release any material clamped beneath the same, thereby providing a simple, inexpensive construction for a stenciling device.

80 In accordance with the patent statutes I have described the principles of operation of my show card stenciling device and I have endeavored to illustrate in the drawings the best embodiment thereof, but I desire to have it understood that these illustrations are only suggestive and that the invention can be applied to other uses and carried out by other means than those above 85 set forth within the scope of the following claims.

90 I claim:

1. A show card stenciling device comprising, a cabinet, a cover adapted to provide a work table for stenciling, and clamping member associated with said cover, said clamping member being designed to operate automatically into engagement with the 105 cover table when said cabinet is opened.

2. A show card stenciling device including, a body portion adapted to form an enclosure for a series of stencils, a clamping means to be enclosed within said body portion, and means for operating said clamping means automatically by opening said body portion and causing said body portion to 110 bear against said clamping means operating means.

3. A stenciling cabinet including, body portion adapted to enclose the stenciling apparatus, a cover portion, a work table, a clamping member, means for supporting said clamping member, and means for causing said clamping member to engage the work table under tension to hold the material to be stenciled thereon when the cabinet 125 is open.

4. A stenciling device including, a cabinet adapted to enclose a series of stencils, a cover, means for hinging said cover to said cabinet in a manner to provide a space be- 130

- neath the body of the cabinet to permit articles being stenciled to pass therethrough, and clamping means adapted to be automatically operated by the tilting of said cabinet to release or clamp material beneath the same.
5. A stenciling cabinet including, a body portion, a cover, a clamping member, and means for automatically operating said 10 clamping member by the tilting of said body portion to move said clamping member into operating position or to release the same.
6. A stenciling device comprising, a work
- table, a cabinet, a clamping member, and means for operating said clamping member by the movement of said cabinet.
7. A stenciling device adapted to provide means for supporting a series of stencils including, a cabinet member, a cover member, a clamping member, arms adapted to support said clamping member, and means adapted to support said arms in a manner to be operated by said cabinet to cause said clamping member to move into and out of operating position.

HOWARD L. FISCHER.
